Primary Examiner — Karen E Eldridge Powers(74) Attorney, Agent, or Firm — Limin Wen(57) CLAIM

We claim the ornamental design for a sports cap with interior pockets, as shown and described.

DESCRIPTION

FIG. 1 is a bottom perspective view of a sports cap with interior pockets; the hat shown in broken lines illustrates the article in which the design is embodied, and forms no part of the claim.

FIG. 2 is a top plan view of the sports cap with interior pockets, with the interior pockets shown separately from the sports cap for clarity of illustration;

FIG. 3 is a bottom plan view thereof;

FIG. 4 is a front elevation view thereof;

FIG. 5 is a right side elevation view thereof;

FIG. 6 is a left side elevation view thereof; and,

FIG. 7 is a rear elevation view thereof. The broken line in FIG. 7 which defines the bounds of the claimed design forms no part thereof.
